UNITED STATES PATENT OFFICE.

MAX KATZ, OF PROVIDENCE, RHODE ISLAND.

DESIGN FOR A COMBINED CLOCK CASE AND PENRACK.

Application filed August 2, 1924. Serial No. 10,352. Term of patent 14 years.

To all whom it may concern:

Be it known that I, MAX KATZ, a citizen of Russia, and a resident of Providence, in the county of Providence and State of Rhode Island, have invented a new, original, and ornamental Design for a Combined Clock Case and Penrack, of which the following is a specification.

Reference is had to the accompanying drawing in which the figure is a perspective view of a combined clock case and penrack showing my new design.

I claim:

The ornamental design for a combined clock case and penrack as shown.

MAX KATZ.
